UNITED STATES PATENT OFFICE.

OTTO E. TRAUTMANN, OF NEW YORK, N. Y., ASSIGNOR TO THOMAS E. MURRAY, OF NEW YORK, N. Y.

VALVE.

1,177,291.

Specification of Letters Patent. Patented Mar. 28, 1916.

Application filed October 28, 1914. Serial No. 868,962.

To all whom it may concern:

Be it known that I, OTTO E. TRAUTMANN, a subject of the Emperor of Germany, residing at New York, in the county of New 5 York and State of New York, have invented a certain new and useful Improvement in Valves, of which the following is a specification.

The invention is a valve and receptacle 10 therefor, and has for its object to make the valve noiseless and free from shock while in operation. When the valve, which is a strip of flexible material, is lifted, the first result is that its end portions meet flat bearing 15 surfaces. Its middle portion is then bent upward, uncovering at its longitudinal edges the outlet ports, so that the fluid entering the inlet on one side of said valve escapes around said longitudinal edges to the outlet.

20 In the accompanying drawings, Figure 1 is a face view of one of the two metal plates, here shown in disk form, in which the valve is seated. Fig. 2 is a face view of the other plate. Fig. 3 shows in plan the two plates 25 placed together, with the valve in position, a portion of the plate of Fig. 2 being broken away. Fig. 4 is a plan view of the valve. Fig. 5 is an enlarged diametral section of valve-receiving plates and valve, the valve 30 being in closed position. Fig. 6 is a similar view, the edges of the plates being broken away and the valve being shown in open position.

Similar letters of reference indicate like 35 parts.

The valve A is a strip of flexible material, preferably thin metal, and is received between the two metal plates B, C, which may be made in the form of disks. In plate C 40 is an elongated port D of less length than the valve A. In plate B are, preferably, two parallel elongated ports E, E, and on one face of said plate is formed a recess, the bottom of which is concave over its middle 45 portion, as shown at F, and at its end portions is preferably flat, as shown at G. Said recess is at right angles to the ports E, E.

When the parts are assembled, as shown in Figs. 3, 5 and 6, the valve is laid upon the 50 flat upper surface of plate C. Plate B is placed upon plate C so that the recess in plate B comes directly over and receives the valve A. As the valve is both longer and wider than the port D in plate C, it com-

pletely closes said port. It is preferable to 55 make the valve of less thickness than the depth of the recess at the end portions G thereof, so that there will be a clearance above said valve when the said valve is in closed position, as shown in Fig. 5. The 60 plates B, C may be united by screws H, and the whole device may then be inserted in a cylinder head, pipe coupling or any casing, partition or wall in which it is desired to establish the valve. The port D being the 65 inlet; when the pressure becomes sufficient, the valve is first raised until its upper side meets the flat end faces G of the recess in plate B, and then the pressure forces the middle part of the valve upward into the 70 concavity F of the recess, the upper faces of the valve in contact with the flat end portions G sliding inwardly, as shown in Fig. 6, to permit of said upward bending of said middle part of the valve. The fluid under 75 pressure is then free to escape into the two outlet ports E, E, around the longitudinal edges of the valve, as indicated by the arrows in Fig. 6.

The operation of the device is practically 80 noiseless and free from shock. The valve being very light, it is almost instantly raised into contact with the flat end portions G of the recess in plate B, and under working conditions, the sound of the impact is in- 85 audible. Afterward, as the valve bends upward, its end portions simply slide upon said flat surfaces, again without noise. When the pressure falls and the valve flattens in, returning to normal position, there 90 is sufficient clearance at its end edges to prevent said edges from meeting the end walls of the recess.

I claim:

1. A valve seat having a flat surface, an 95 elongated valve of elastic flexible material, and a cover having a recess concave at its middle portion and having flat bottom faces at its end portions, the said valve extending across the concave portion of said recess and at both ends loosely received between the flat bottomed ends of said recess and said seat.

2. A valve seat having a flat surface, an 100 elongated valve of elastic flexible material, and a cover having a recess concave at its middle portion and having flat bottom faces at its end portions, the said valve being

received between the flat bottomed ends of
said recess and said seat and extending
longitudinally across the concave portion of
said recess, and there being a clearance be-
5 tween said valve and said flat bottom faces
of said recess when said valve is in normal
closed position.

In testimony whereof I have affixed my
signature in presence of two witnesses.

OTTO E. TRAUTMANN.
